TAPE TRANSMITTER

Louis M. Potts, Evanston, Ill., assignor to Tele-type Corporation, Chicago, Ill., a corporation of Delaware

Application November 7, 1940, Serial No. 364,631

14 Claims. (Cl. 178—17)

This invention relates to printing telegraph apparatus and particularly to automatic selector mechanism responsive to the components of a code combination for establishing signal impulses.

In signal transmission systems and apparatus, it is the function of a transmitting distributor to apply upon a signaling line or circuit code combinations impulses which constitute each signal. The application of these code combinations of impulses to the line together with their phase regulating impulses should be obtained at precisely the time interval at which receiving equipment is capable of operation, that is, each impulse should be routed precisely to its particular apparatus. The maintenance and regulation of this cyclic operation of transmitting and receiving apparatus is frequently obtained by the use of a power driven shaft at each station, transmitting and receiving, with speed regulating mechanism to assure the maintenance of time precision.

These regulated power shafts rotate transmitting and/or receiving equipment by the instantaneous operation of clutching means and through this mechanism there is, in turn, operated a device for sensing each code combination signal either in accordance with the operation of a set of feeler levers, or in accordance with the manipulation of a keyboard, causing a set of electrical contacts to be opened or closed for each signal combination. In order to effect instantaneous responses to control impulses, the power operated shaft must be set in operation and arrested without undue sluggishness and these devices must therefore be light in weight and compact in design. Also, the distance of movement must be a minimum; otherwise the ultimate response mechanism of the distributor apparatus may affect detrimentally the proportions of the resulting electrical signals reproduced.

It is, accordingly, a principal object of the present invention to provide a transmitting distributor selection apparatus which is adaptable to both tape control and manual key lever supervision.

A further object of the present invention is to provide in a single contact transmitting apparatus a drop-off cam type of selection with a common contact controlling lever which is instantaneously responsive to each of the several components of a code signal.

A principal feature in the present invention is the provision of a set of cams, each related to a

permutation code signal element and each having a drop-off shoulder located at an individual place in the signal cycle with respect to the other cams. The periphery of each said cam is followed by a pair of levers, one or the other of which may be conditioned in accordance with supervisory control, such as a perforated tape, causing to be moved a common contact operating member. The latter remains in a set position for the duration of one or more signal impulses and is changed to its alternative position only in response to a signal component which differs from its preceding signal component. Accordingly, the boundaries between the signal impulses of a line is determined solely by the drop-off shoulder of each cam and not by the riser surface thereof. Since it is easier to locate the drop-off shoulder of a series of cams with precision than it is to so locate inclined riser surfaces with precision, the herewith proposed principle of construction affords greater accuracy and is subject less critically to variations and changes due to wear.

These and other objects of the instant invention are obtained by operating a clutch controlled, cyclically rotatable shaft having a spiral distribution of cams, each with its peripheral drop-off occurring at an individual instant or period during the rotation of said shaft and each operative to regulate the performance of two signal transferring levers. Marking and spacing components alternatively condition one and disable the other of said two levers of each distributor and the conditioned one may then respond to the exclusion of the other during its associated impulse interval. A slight movement of the conditioned one of said two levers is then translated into a corresponding movement on the part of a common regulating member which, in turn, causes to be moved a common contactor into corresponding marking or spacing position. The alternative selection between each pair of conditionable levers is effected through the function of a single sensing element which may probe the location of a code perforation in a tape, respond to the position of a keyboard bar, or in turn be regulated by any supervision element depending upon the nature of the apparatus in which this principle is incorporated.

For a more comprehensive understanding of the present invention, reference may be had to the accompanying drawings and to the detailed specification following hereinafter wherein like reference characters represent corresponding parts throughout, and wherein,

Fig. 1 is a side elevational view of a perforated-tape controlled transmitter unit having embodied therein certain features of the present invention;

Fig. 2 is a transverse sectional view taken approximately on line 2-2 of Fig. 1 and illustrating the distributor shaft in one possible condition of operation;

Fig. 3 is a view similar to Fig. 2 illustrating a different condition of operation;

Fig. 4 is a fragmentary end elevation of the power driving train with certain parts of the apparatus broken away;

Fig. 5 is a diagrammatic sketch of a modified system of operation;

Fig. 6 is a diagrammatic detail view of a further modified apparatus having embodied therein certain elements of the present invention;

Fig. 7 is a diagrammatic circuit illustration of a tape perforator and transmitter operating in accordance with certain improved embodiments forming part of the present invention;

Fig. 8 is a diagrammatic timing chart illustrating the periodicity of certain mechanical functions in the structural embodiment of Figs. 1 to 4, and

Fig. 9 is a detailed perspective view of a portion of the cam sleeve together with its related apparatus.

Attention is now directed specifically to Figs. 1 to 4 and 7 of the accompanying drawings wherein the reference character 11 denotes a base plate of a transmitter apparatus upon whose surface are mounted three supporting frames indicated 12, 13, and 14. A shaft 15 extends longitudinally of the plate 11 and is journaled within an alignment of bearing apertures located in the frames 12, 13, and 14. Rotary motion originating with a prime mover represented by the shaft 16, Fig. 1, is imparted through the driving worm 17 to a driven gear 18 secured to said shaft 15. The direction of rotation is clockwise as viewed in Figs. 2 to 4, and the driving clutch element 19 being an integral part of shaft 15 partakes of this rotation continuously.

A driven clutch element 21, having an end surface radially serrated to cooperate with a corresponding surface on driving clutch element 19 receives, corresponding rotary movement when released from its dormant position as illustrated in Fig. 1 by the withdrawal of interfering armature 22 whose upright extremity is normally spring urged to be interposed in the path of a declutching lug 23 which, by reason of its inclined surface first withdraws driven clutch element 21, then by positive engagement with the upright extremity of armature 22, holds the former member from rotating with the driven element 19.

Armature 22 may be withdrawn from interference with lug 23 upon the energization of tape slack controlled magnet 24, see Fig. 7, in consequence of the release of a slack sensing arm 28 whence clutch element 21 is brought into engagement with element 19.

Magnet 24 which controls armature 22 is energized over a circuit 25 except when this circuit is broken by the separation of contactor 26 from its contact point 27. Contactor 26 is carried by said tape slack lever 28 pivoted at 29 and when the slack in tape loop 31 exceeds a predetermined quantity arm 28 is permitted to droop to an extent which permits contact blade 26 to engage

its contact point 27. Upon the shortening of tape loop 31, however, the lowermost extremity of arm 28 is engaged thereby, causing said arm to be rotated clockwise about pivot 29 until contactor 26 is separated from contact point 27 at which time magnet 24 is deenergized permitting armature 22 to be interposed into the path of clutch disengagement lug 23, as afore-stated.

The end of clutch driven member 21 opposite its serrated face is formed with a tongue 32 receivable within a slot 33 in the flanged extremity of a cam sleeve assembly 34, Fig. 1. Sleeve 34 carries a series of cams including five cams indicated 35 to 39 each of which is operative upon an individual pair of transfer levers 41 and 42, cam 43 which serves to place invariably a transmitting contact into stop position at the conclusion of a signal cycle, cam 44 which serves to invariably place the transmitting contact into spacing position at the start of a signal cycle, cam 45 which during a given period in the cycle through the agency of its transverse bail 46 serves to withdraw a set of feeler levers 58 from the perforated strip, and cam 47 which through bell crank lever 101 moves a feeler lever guide pin 49 steadily forward during the time that any of the set of feeler pins are extending into the strip.

Having thus introduced each of the cams carried upon assembly sleeve 34, more particular reference to the performance of each will be had later during the detailed description of its apparatus. The sequence of operations of the several cams 35 to 39, 45 and 47 is portrayed on the accompanying timing chart, Fig. 8. On this chart a complete cycle is represented by the time interval between line a—a and line b—b. It is to be noted that transmission may continue without interruption so long as slack in the loop 31 prevails, and also that one signal cycle follows another during transmission after the manner of conventional start-stop distributors. In terms of the signal curve 51, Fig. 8, during consecutive signals, line b—b of one signal coincides with the line a—a of the succeeding signal.

Curve 51 of Fig. 8 represents a typical signal in which stop current is of a predetermined marking polarity, start current is of a predetermined polarity different from that of stop current and the five signal intervals designated 1, 2, 3, 4, and 5 may, of course, be constituted of any permutable arrangement of marking and spacing current. The illustration of Fig. 8 contemplates alternate changes during successive signal intervals of the code signal for the sake of facile illustration.

Curve 51 portrays the action of a contactor 52, Fig. 4, which is carried upon a bracket 53 integral through horizontal bar 54 with the selector ball 55.

Contactor 52 may fluctuate between a pair of contact point screws 56 and 57 each associated with an individual current characteristic such as plus, minus or zero current. To accord with standard practice contact screw 57 will be connected with marking or plus current while contactor 56 will be connected to no-current.

As has been said, the behavior of contactor 52 during the start and stop impulses of each signal, as portrayed for example by curve 51, is inevitable but its behavior with respect to the five code combination signal impulses will vary in accordance with the positioning of a set of five tape feeler levers 58. Feeler levers 58, as portrayed

in Figs. 2 and 3, are all of identical contour. Each carries at its uppermost extremity a feeler pin 59 of small diameter so as to be easily admitted into the code perforations of a control form, such as a perforated tape. Each feeler lever body has an elongated hole 61 through which passes the anchor pin or shaft 62 which determines the extent and to some degree the direction in which each lever 58 may be moved. Another shaft 49 passing transversely through the several feeler levers as does shaft 62 is also located in an elongated slot designated 63 in the several feeler levers 58. Since elongated slots 61 and 63 are arranged in parallel relationship and in a generally longitudinal direction with respect to the feelers, it will be understood that pin 49 will in no wise restrict the vertical motion of the feeler levers 58 but will restrict said levers against rotation about shaft 62 as a center.

In addition to the aforescribed appurtenances each feeler lever is also provided with a sidewardly extending shoulder lug 64 across the top of which there is disposed the transverse restoration bail 46, mentioned above. The lowermost extremity of each feeler lever comprises a plate section indicated 65 directed leftwardly as viewed on Figs. 2 and 3, and each said plate section is provided with right angular abutment shoulders 66 and 67. An individual spring 68 connected between an ear formation in each lever 58 and an anchor bracket 69 urges each one of said levers 58 upwardly but during a brief interval of each cycle all of the feeler levers are restrained against the influence of their several springs 68, that is, when bail 46, a part of a lever 48 is urged downwardly depressing all of the feeler lever lugs 64, as indicated in Fig. 2. One end of lever 48 terminates with a cam follower projection 71 which rides the periphery of aforescribed cam 45.

The period during each cycle when the depression in cam 45 becomes effective to permit all of the feeler levers 58 to rise is indicated by the horizontal portion of curve 72, see Fig. 8. The brief interval during which the feeler levers are depressed or withdrawn is represented by the comparatively short peak in said curve 72. When freed by the lifting of bail bar 46 each of the several feeler levers 58 seeks to rise to an upper level such as indicated in Fig. 3. This extent of movement is permitted only when a perforation is encountered in the tape which passes between the guide plates 74 and 75. When the feeler projection 59 encounters no perforation in the tape, however, a particular lever 58 will be permitted to rise only until its upper extremity encounters the surface of the tape in which case it will assume a position approximately such as that illustrated in Fig. 2.

Of the two possible positions which each feeler lever 58 is capable of assuming, the one referred to previously, when projection 59 extends through the tape, is commonly termed marking while the other, when projection 59 is blocked by the tape, is referred to as spacing. This classification is in conformity with the same terminology as before applied to line signals of current and no-current polarity. When a feeler lever 58 is in its marking position, shoulder 66 of its lowermost extremity will be presented in the position illustrated in Fig. 3, whereat it blocks the cooperating shoulder 76 of the class of transmitting bail transfer levers designated 41, while shoulder 67 of the plate 65 is sufficiently raised so as to clear shoulder 77 of lever 42, as best illus-

trated in Fig. 3. On the other hand, when said feeler is in the spacing position, shoulder 66 will be below shoulder 76 so as not to interfere with the movement of lever 41 but instead lowermost shoulder 67 of feeler lever 58 will then engage the co-operating shoulder 77 of the associated transfer lever 42. Accordingly, depending upon the position of each feeler lever 58, one or the other of each pair of transfer levers 41-42 will be permitted to rotate counterclockwise about the common pivot 78 to the exclusion of the other one.

While selector transfer levers 41 and 42 are substantially different in contour they resemble each other, nevertheless, throughout a brief intermediate portion and particularly in the proximity of their follower projections 79. In fact, the projections 79 of all levers 41 and 42 are in the same longitudinal alignment and each pair relating to a set of levers 41 and 42 is designed to rest upon the periphery of a particular one of the set of five distributor cams 35 to 39, inclusive, is identical and is as indicated in Figs. 2 and 3. However, the several cams 35 to 39 are successively displaced each from the other by a constant angular progression. Accordingly, the several cams are so arranged that the dwells or low portions 81 in their peripheries occur successively at any particular point as the cam assembly 34 is rotated by the clutch elements, 19-21.

At an assigned interval in the selective cycle, each particular one of the cams 35 to 39 will present its nadir or low portion 81 to its associated pair of transfer levers 41-42. Since for each impulse but one of said two levers 41 and 42 may be free with respect to the interfering shoulders 66 and 67 of its associated feeler lever portion 65, that particular one of said pair of levers

41-42 will be permitted to rotate counterclockwise about pivot 78 under the influence of its individual spring 82 or 83 and as a result will cause to be engaged its corresponding one of the two transfer bail edges 84 or 85. When bail edge 84 is engaged by its lever 41, the bail 55 will be rotated clockwise about pivot 88, causing its latching projection 86 to be moved to the uppermost of the detent notches in detent lever 87. On the other hand, if the lowermost bail edge 85 is engaged by its associated lever 42, bail 55 will be rotated counterclockwise about pivot 88 causing detent projection 86 to register and be engaged in the lowermost of the detent notches of detent pawl 87. The latter member is urged by a spring 89 in counterclockwise direction about its pivot, holding bail member 55 in either of its positions as determined by one or the other of the previously operated levers 41 or 42, in which position said bail 55 will continue until it is operated by a lever 41 or 42 differing in position from said previously operated one of said levers. It is to be understood that the force of either one of the springs 82 or 83 is sufficient to overcome the effect of said detent spring 89 so that upon the operation of one or the other of said levers 41 or 42, the retaining projection 86 may be moved quickly in a corresponding manner.

Since but one of each pair of levers 41 and 42 may be operated to the exclusion of the other and since the depressions in cams 35 to 39 are arranged in a spiral sequence, there is produced during the rotation of cam assembly 34 a set of signaling impulses by the operation of contactor 52 as influenced by the fluctuations of bail 55.

which in turn is dependent upon the operation of said set of pairs of levers 41 and 42.

Although in the operation of the instant disclosed apparatus there is contemplated the customary intermittent motion on the part of a set of feeler levers 58 as in the case of conventional tape transmitter mechanism, a novel practice and a means for its execution is proposed herewith in the use of a non-intermittent or continuously moving tape in conjunction with said intermittent feeler levers 58. It will be noted that a driving gear 91, Fig. 4, is formed as a part of assembly 34. This element meshes with a larger driven gear 92 which together with an integrally associated driving pinion 93 is carried upon an idler shaft 94. Driving pinion 93 meshes with a driven pinion 95 whose shaft 96 extends transversely across the tape sensing apparatus and has fastened to it the sprocket feed 97. So long as the motion of assembly sleeve 34 is sustained and continuous, the motion of shaft 96 is sustained and continuous. Accordingly, since tape feed sprocket 97 is an integral part of shaft 96, the motion of the tape as induced by the teeth of sprocket wheel 97 is correspondingly even and sustained in contradistinction to the conventional intermittent or step-by-step movement.

The sprocket teeth of wheel 97 are adapted to fit into perforations customarily provided in the approximate longitudinal center of a control strip for the purpose of advancing the strip both during preparation and subsequently during its use as a control medium. Since the tape feelers 59 extend into the perforations of the tape during a substantial period of each signal cycle and since the tape is continuously in motion during this period, means have been provided for positively moving the feeler levers 58 in the same direction as that in which the tape is moving and at substantially the same rate of movement so that relative alignment is positively maintained between the feeler lever pins 69 and the code perforations in the tape.

To understand how this is accomplished, reference will again be directed to the feeler lever alignment pin 49 mentioned above. This pin which passes through the slot 63 of the several feeler levers 58 is anchored in a bell crank lever designated 101. The vertical arm of bell crank lever 101 carries the afore-mentioned pin 49 and to it is tied one end of a tension spring 102, the other terminal of which is anchored to the framework of the apparatus. Accordingly, spring 102 urges counterclockwise rotation to bell crank 101, causing it to seek to rotate about its pivot 103. Such rotation may advance only until the follower nose 104 which is formed with the other arm of bell crank 101 engages the periphery of afore-described cam 47, the contour of which is such as to induce a movement on the part of bell crank 101 to correspond with the curve 105 indicated in Fig. 8. From this it will be understood that the motion of the several feeler levers 58 during the five impulse intervals of a code signal is slowly in a direction from right to left, as viewed in Figs. 2 and 3, and that thereafter, during a brief interval corresponding generally to the stop-start, or some part of either interval of each signal cycle, all of said feeler levers 58 having meanwhile been extracted by the operation of bail 46, as portrayed by curve 112 of Fig. 8, they are forthwith returned from a position as indicated approximately in Fig. 3 to one such as indicated approximately in Fig. 2.

In Fig. 1 the reference character 41a denotes a special transfer lever resembling in contour the class of levers 41 of which one is associated with each cam 35 to 39, as afore-described. Correspondingly, the reference character 42a denotes a special transfer lever resembling in contour the general class of levers 42. At an interval during each signal cycle preceding the five impulse intervals of the code combination cam 44 presents its recess to the projection 79 of lever 41a causing said lever to engage edge 84 of the contact operating bail so that it is rocked clockwise, Figs. 2 and 3. As a result contactor 52 engages point 56 and a spacing or start impulse is invariably produced. Thereafter follow the five code impulses and then cam 43 presents its drop-off to lever 42a causing the latter to rotate the contact bail counterclockwise. This moves contactor 52 into engagement with point 57 causing a marking or stop impulses to be generated. In this way levers 41a and 42a operate invariably to produce the essential phasing (start and stop) impulses of the system.

Having explained the performance of each one of the cams 35 to 39, 43 and 44, inclusive, in connection with their individual functions of determining the operative instants of levers 41, 42, 41a, and 42a, attention is now directed to the curve 110, Fig. 8. Here there is represented by the sharp saw tooth portions of the curve the instants of occurrence of each of said cam drop-offs, and by comparing this curve with the one indicated 51 it will be observed that the length of each signal impulse or component is determined by the distance from one cam drop-off to a succeeding one. Thus, while conventional types of cam operated transmitting apparatus depends for accurate signal reproduction upon the full contour of their controlling cams, the instant apparatus depends solely upon the location of each cam drop-off and not upon the further characteristics of each cam contour.

A principal feature of novelty which is disclosed in the foregoing preferred embodiment is one which may find application in printing telegraph apparatus other than tape controlled transmitters. To illustrate, attention is directed to the disclosure of a single magnet controlled selector mechanism in Fig. 5. Here a shaft which carries the cam assembly is indicated 151 while against the periphery of the cams there may be observed a set of bell crank levers disposed in pairs which are indicated 152 and 153. Individual power springs 154 tend to rotate levers 152 and 153 of each pair in a counterclockwise direction about their common pivot 155. Through the intervention of an armature 156, which is controlled by the line signals that are impressed upon magnet 151, bell crank lever 152 or 153 may be individually selected upon the occurrence of the notch 158 in alignment with its probing projection 159. As in the case of the preferred embodiment, it will be recalled that but one of the two levers may be selected in response to any particular signal impulse and that the other of each pair is thereby excluded from selection.

When one or the other of the bell cranks 152 or 153 is rotated by its power spring 154, the projection 161 or 162 of the opposite end of said bell crank will, accordingly, shift a lever 163 which is pivoted at 164 and which is detented by element 165 to accordingly position its associated selector bar 166. The manner in which a set of selector bars 166 accomplish the func-

tion of selection forms no part of the present invention and accordingly reference thereto is deemed unnecessary. Reference may be had to U. S. Patent No. 1,884,807 for an understanding of the manner of operation and the details of construction of a typical selector bar apparatus to which this embodiment of the present invention may be applied.

In its operation the embodiment disclosed in Fig. 5 follows essentially the timing and general arrangement of the principal embodiment disclosed in Figs. 1 to 3, inclusive. The notches of the several cams 158 are arranged in a spiral progression and the rotation of shaft 151 is regulated to synchronize with the fluctuations of a line magnet armature 156 as is well known in the practice of printing telegraph apparatus. As armature 156 fluctuates, it may be positioned to block either one of the pair of bell cranks 152 or 153 so the other one of said pair through its projection 161 or 162 rocks its associated selector bar 166 to the right or to the left and, there being a set of said bars 166 to be permutably positioned, the result of a cycle of operation of shaft 151 is the corresponding positioning of a set of code bars 166. Ultimately the notches in said several bars 166 are disposed to present a selection to a transverse bar in a manner well known in printing telegraph apparatus.

In Fig. 6 there is illustrated a further modification of the present invention featuring the application of certain essential novel principles in a direct keyboard telegraph transmitter. Here the cyclically controlled transmitting shaft is designated 171. It carries a spirally arranged succession of recessed cams represented by the foremost one, indicated 172. Each of said cams is adapted to serve a pair of transfer levers designated 173 and 174.

The levers 173 and 174 in this case, as in the preceding example of bell cranks, extend one farther than the other as indicated at 175 and 176. A power spring 177 individual to each one of said levers 173 and 174 tends to rotate it in a counterclockwise direction as indicated. The keyboard apparatus is denoted by the representative bar 178 of which there customarily are provided a set of five (in a five unit code system), and a universal bar which is invariably operated upon the depression of any key lever to start the distributor into rotation, each bar 178 having associated with it an individual setting lever 179 which is pivoted on a common shaft 181. Each bar 178 is provided with two tie pins 182 between which the lowermost arm of its lever 179 extends while the upper end of lever 179 is provided with a pair of overhanging lugs 183 and 184. Following each keyboard operation, i. e., the depression of a key lever, a locking knife 203 is caused to descend upon one side or the other of the several uppermost projections 190 of said levers 179 holding them secure in their set position while the code transfer is completed as will now be explained. The spread of said lugs 183 and 184 is such that one or the other of them may overlie the corresponding projections 175 or 176 of lever pairs 173 and 174. By thus overlying the extremity of one or the other of said bell crank levers that one is prevented from responding to its associated power spring 177 when during the course of travel of the cam assembly its associated cam 172 presents its dwell or recessed portion to said lever opposite its lug 186. The one of said pairs of selectable

levers 173 and 174 which is not obstructed by an overhanging lug 183 or 184 is then free to respond to the urge of its power spring 177 and rotate counterclockwise about pivot 187. This will correspondingly rotate contact control arm 188 about its pivot 189 overcoming the spring detent 191 and setting the contactor 192 to engage one and disengage the other of its associated pair of contact points 193 and 194.

Accordingly, there will be installed upon the contacting member 192 a signaling condition representative of its associated keyboard bar 178. As shaft 171 rotates and the several cams 172 are successively brought into alignment with the corresponding lugs 186 of their pairs of levers 173 and 174 so, too, will the signaling impulses of the complete signal be installed upon the contactor 192 in the manner in which it engages one or the other of its associated contact points 193 and 194.

While the present invention has been explained and described with reference to certain specific embodiments, it is to be understood nevertheless that certain variations and modifications may be made without departure from the sphere or scope thereof. Accordingly, it is not intended to be restricted in any way to the specific illustrations of the accompanying drawings nor to the particulars of the foregoing detailed specification except as indicated in the hereinafter appended claims.

30. What is claimed is:

1. In a tape transmitting apparatus, a pair of line contacts, a plurality of pairs of contiguous bars each pair associated with an impulse of a permutation code, a plurality of power driven cams each associated with one of said pairs of bars to simultaneously condition said bars of each pair, supervisory means for blocking one of the bars of each pair to permit the other solely to respond to their common cam, and means including said single pair of contacts for generating line signals under the control of said pairs of bars.

2. In a tape transmitting apparatus, a plurality of pairs of parallelly acting elements having a single pivotal axis common to all, each pair associated with an impulse of a permutation code, a power driven cam associated with each one of said pairs of elements and presenting a permissive clearance to them simultaneously, means to further condition each pair of said elements for supervision by said associated cam, and means for generating line signals under the control of said pairs of elements rotatable about the same pivotal axis.

3. In a transmitting apparatus, a series of pairs of bars associated with corresponding components of a permutation code, a power driven cam associated with each one of said pairs of bars, means to select one bar and block the other bar of each pair of bars for movement under the supervision of its said associated cam, and means for generating permutation code line signals under the control of conditioned bars of said pairs of bars.

4. In a printing telegraph selector mechanism, a series of pairs of code transfer elements, means to block one and condition another one of each pair of said code transfer elements for effective operation, apparatus to present a path for movement to each pair of said transfer elements successively, and contacts for generating line impulses in accordance with the operation of the one of said transfer elements of each pair which is conditioned by said means.

5. In a printing telegraph selector mechanism, a series of pairs of transfer elements, signal con-

trolled means to block one and condition the other one of each pair of said transfer elements for effective operation, means to present a path for movement to each pair of said transfer elements, and a pair of contacts for generating impulses in accordance with the movement of the one of said transfer elements which thus is conditioned.

6. In a printing telegraph selector mechanism, a plurality of pairs of code transfer elements, impulse supervised means to condition one of each pair of said code transfer elements for effective operation, means to present successively a single clearance for movement to each pair of said transfer elements, and means for generating line impulses in accordance with the operation of said conditioned transfer elements of each pair according to said single clearance presenting means by one of the elements of each pair of elements being selected successively.

7. In a code telegraph system, a tape transmitter, a cyclically rotatable shaft in said tape transmitter, a pair of line contacts, and apparatus for operating said line contacts in accordance with the perforations in a tape comprising a set of feeler levers, a set of pairs of contact conditioning levers, each pair associated with one of said feeler levers, and cam means carried by said cyclically operating shaft for permitting each of said pair of conditioning levers to assume a position in accordance with its associated one of said set of feeler levers.

8. In a signal transmission system, a signal generating contact pair, mechanism for operating said contact pair, a plurality of pairs of supervisory impulse transfer levers for conditioning said mechanism, the levers of each of said pairs being parallelly rotatable about a common shaft, perforated tape controlled means for selecting of each pair of said levers one to operate said mechanism, and a control shaft having a plurality of cams each corresponding to and presenting a permissive clearance concurrently to a pair of said levers for appropriating a cycle interval to the selecting of said levers.

9. In a signal transmission system, means to generate line signal impulses, a plurality of pairs of parallelly acting transfer levers having in common a single pivotal axis for supervising said signal generating means, tape controlled means for selecting of each pair of said levers one to operate said generating means, and a control shaft having a plurality of cams each for appropriating a cyclic interval to the operation of one lever of its said pair of said levers about the said common pivotal axis.

10. A permutation code selector apparatus comprising, a series of pairs of signal component transfer means, a cyclically operated device for permitting each pair of said transfer means to move into effective position for operation, and a supervisory element associated with each pair of said series for blocking one of said pairs against effective operation.

11. In a keyboard controlled apparatus, a series of code bars, a corresponding series of parallelly acting pairs of transfer elements pivoted about a common pivotal axis, means under the control of each code bar of said series for enabling one of said pairs of transfer elements, a cyclically operated device for conditioning each pair of said transfer elements successively and parallelly about the said common pivotal axis, and an apparatus common to said series of pairs of transfer elements and responsive only to the operation of conditioned transfer elements.

12. In a keyboard apparatus, a series of pairs of transfer elements, a cyclically operated device for conditioning each pair of said transfer elements successively, means to block one element of each pair under the control of a keyboard manipulation, and a response apparatus operated by the unblocked one of each pair during its cyclic conditioning.

13. In a start-stop telegraph system, a transmitter apparatus comprising a series of cams, certain of said cams relating to components of a code combination signal, pairs of levers associated with said cams, certain other of said cams relating to the phasing components of a code combination signal, single levers associated with said other of said cams, a pair of transmitting contacts, and means to operate said contacts successively under the control of said pairs of levers to produce variable responses and under control of said single levers to produce invariable responses.

14. In a tape transmitting apparatus, signal generating contact means, a series of collateral pairs of levers for operating said signal generating contact means, a series of cams each having portions for releasing said levers during an individual cyclic instant, and portions for restoring said levers during an individual subsequent instant, means to control the operation of said signal generating contact means by means of said levers during the release portion of said cams and independently of said restoring portions of said cams.
